PISTON-TYPE FLUID PUMP

Robert F. Rasmussen, Minneapolis, Minn., assignor to
Hypro Engineering Inc., Minneapolis, Minn., a corpora-
tion of Minnesota

Filed Jan. 6, 1960, Ser. No. 58,946

Term of patent 14 years

(Cl. D65—1)

Figure 1 is a front elevation, showing my new design
for a piston-type fluid pump;

Figure 2 is a side elevation thereof;

Figure 3 is a rear elevation thereof; and

Figure 4 is a top plan view thereof.

I claim:

The ornamental design for a piston-type fluid pump,
substantially as shown.
